SHOE FORM

Alfred G. Legge, Brockton, Mass.

Application March 5, 1932, Serial No. 596,969

4 Claims. (Cl. 12—128.5)

This invention relates to hollow shoe forms having a thin flexible wall adapted to be spread into engagement with the upper of the shoe. It is an object of the present invention to provide 5 improved means for maintaining the walls of the toe part of the form in engagement with the toe part of the shoe.

The invention will be more clearly understood from the following description in conjunction with 10 the accompanying drawings: in which,

Fig. 1 is a plan view, partly broken away, of a shoe form embodying the invention;

Fig. 2 is a sectional elevational view of the same;

Fig. 3 is a view looking at the bottom of the 15 form;

Fig. 4 is a view similar to Fig. 3 showing a modified construction;

Fig. 5 is a plan view of another modified construction; and

Fig. 6 is a sectional view taken upon the line 6—6 of Fig. 5.

Before explaining in detail the present invention, it is to be understood that the invention is 25 not limited in its application to the details of construction and arrangement of parts illustrated in the accompanying drawings, since the invention is capable of other embodiments and of being practised or carried out in various ways.

Also it is to be understood that the phraseology 30 or terminology employed herein is for the purpose of description and not of limitation, and it is not intended to limit the invention beyond the terms of the several claims hereto appended as 35 considered in view of the prior art and the requirements thereof.

In the accompanying drawings a shoe form is 40 shown comprising a hollow toe part 10 of sheet celluloid or the like, the opposite side walls of which are provided with bottom inturned flanges 11 and 12. The flanges 11 and 12 are connected by a cross brace for imparting rigidity to the form which may be adjustable so as to expand the form to the width of the shoe in which it is 45 to be used. In the forms shown in Figs. 1 to 4 the cross brace comprises an arm 14 pivotally mounted at one end upon a rivet 15 secured in the flange 11 and carrying at its other end a cylindrical shaped member 16 adapted to be 50 moved to engage any one of a plurality of notches 17 in a slot 18 formed in a bracket 19 suitably secured to the flange 12, as by rivets 20. An arm 21 is pivotally mounted at one end upon a rivet 22 secured in the flange 11 and extends inwardly 55 therefrom and then forwardly beneath the mem-

ber 14 and is provided at its free end with a downwardly extending prong 23 adapted to engage the insole 24 of a shoe 25 in which the form is inserted. The arm 21 is provided with an intermediate upwardly extending portion 26 adapted to engage the cross member 14.

When the form is being prepared for shipment the arm 21 is swung to one side so that the prong 23 rests upon the top surface of the flange 11. When the form is inserted in a shoe so that its 10 toe part is snugly in engagement with the shoe upper, the arm 21 is moved off the flange 11 so as to bring the upwardly extending portion 26 in engagement with the cross member 14 and permit the prong 23 to engage the insole 24 of a 15 shoe.

In the form shown in Fig. 4 the arm 21' is shaped similar to the arm 21 and is provided at its forward end with a downwardly extending prong 23' adapted to engage the insole of a shoe 20 and with an intermediate upwardly extending portion 26' adapted to engage the cross member 14. The rear end of the arm 21' is pivotally mounted upon a rivet 30 secured in one end of an arm 31, the other end of which is pivotally carried by a rivet 32 secured in the flange 11, preferably, positioned between the cross member 14 and the toe end of the form.

In Figs. 5 and 6 a form of modified construction is illustrated. In this form the side walls are 30 spread by a toggle, one arm 33 of which is pivotally mounted upon a rivet secured in the flange 12 and the other end of which is pivotally connected at an intermediate point of the other arm 34 which is pivotally mounted upon a rivet secured 35 in the flange 11. The arm 34 extends over the arm 33 and beyond the same and is provided with a downwardly bent portion 35 having a prong 36 at its free end adapted to engage the insole of a shoe. When this form is inserted in a shoe 40 snugly in engagement with the shoe upper the prong 36 engages the insole and holds the form in desired position inasmuch as it is formed as an integral part of the toggle mechanism. The downwardly bent portion 35 of the arm 34 is adapted to 45 engage the arm 33 and positively lock the form in position with a shoe.

What I claim is:

1. A shoe form comprising a hollow toe part having its opposite side walls provided with bottom inturned flanges, a cross member connecting said flanges, an arm pivotally secured to one of said flanges and extending inwardly therefrom, a member pivotally secured to the free end of said arm and adapted to extend beneath said cross 55

member, said member having a downwardly extending prong adapted to engage the insole of a shoe and having an intermediate upwardly extending portion adapted to engage said cross member to prevent rearward movement of the form.

2. A shoe form comprising a hollow toe part having its opposite side walls provided with bottom inturned flanges, adjusting means connecting said flanges adapted to adjust the width of the form, said adjusting means comprising a slotted member secured in raised position upon one of said flanges, a cross brace connecting said member and the other flange, a rivet pivotally securing one end of said cross brace to said other flange, and a rivet carried by the other end of said cross brace and engaging the slot in said member.

3. A shoe form comprising a hollow toe part having its opposite side walls provided with bottom inturned flanges, adjusting means connecting said flanges adapted to adjust the width of the form, said adjusting means comprising a slotted member secured in raised position upon one of said flanges, a cross brace connecting said

member and the other flange, a rivet pivotally securing one end of said cross brace to said other flange, and a rivet carried by the other end of said cross brace and engaging the slot in said member, the area of said first mentioned flange engaged by said first mentioned rivet being raised to reduce the frictional contact of the rivet with the insole of the shoe. 5

4. A shoe form comprising a hollow toe part having its opposite side walls provided with bottom inturned flanges, adjusting means connecting said flanges adapted to adjust the width of the form, said adjusting means comprising a slotted member, rivets for securing said member to one of said flanges, a cross brace connecting 15 said member and the other flange, a rivet pivotally securing one end of said cross brace to said other flange, the area of said flanges engaged by said rivets being raised to reduce the frictional contact of the rivets with the insole 20 of a shoe in which the form is inserted, and a rivet carried by the other end of said cross brace and engaging the slot in said member.
